(57) **CLAIM**

What is claimed is the ornamental design for a rear housing for an electronic device, as shown and described.

DESCRIPTION

FIG. 1 is a perspective view of a rear housing for an electronic device showing my present design;

FIG. 2 is a front view thereof;

FIG. 3 is a rear view thereof;

FIG. 4 is a left view thereof;

FIG. 5 is a right view thereof;

FIG. 6 is a top plan view thereof;

FIG. 7 is a bottom plan view; and,

FIG. 8 is a perspective view seen from another direction. The broken lines depict environmental subject matter only and form no part of the claim.
